UNITED STATES PATENT OFFICE.

ABRAHAM MISROCH AND ADOLPH KAHN, OF NEW YORK, N. Y.

FOLDING PACKING-BOX.

1,171,228.

Specification of Letters Patent.

Patented Feb. 8, 1916.

Application filed February 1, 1915, Serial No. 5,452.

To all whom it may concern:

Be it known that we, ABRAHAM MISROCH and ADOLPH KAHN, citizens of the United States, and residents, respectively, of the city of New York, borough of the Bronx, in the county of the Bronx and State of New York, and of the city of New York, borough of Manhattan, in the county and State of New York, have invented a new and Improved Folding Packing-Box, of which the following is a full, clear, and exact description.

This invention relates to packing boxes of that type which are folded from flat blanks into box form when desired for use, and the invention has to deal more particularly with a closing or locking means for boxes of this character.

The invention has for its general objects to improve and simplify the construction of folding or collapsible packing boxes in which a handle is employed as the sole locking means for holding the box closed, the design being such that the cost of manufacture is reduced to a minimum and the box can be easily and quickly folded into box form from a blank and locked closed after receiving its contents.

With such objects in view, and others which will appear as the description proceeds, the invention comprises various novel features of construction and arrangement of parts which will be set forth with particularity in the following description and claim appended hereto.

In the accompanying drawing, which illustrates one embodiment of the invention and wherein similar characters of reference indicate corresponding parts in all the views, Fig. 1 is a perspective view of the box locked closed by the handle; Fig. 2 is a perspective view showing the handle in its unlocking position; Fig. 3 is a perspective view of the handle-carrying flap or lid of the box; Fig. 4 is a bottom perspective view of this handle-carrying flap; Fig. 5 is a perspective view of the handle removed; and Fig. 6 is a view of a blank from which the box is formed.

In the present instance the box is shown as of rectangular shape, but it is to be understood that the shape may be varied to suit any desired requirements, and cardboard or any other material may be employed.

Referring to the drawing, and more particularly to Fig. 6, the blank comprises a

body section A and side sections B and C, the body section consisting of a bottom 1, ends 2 and 3 and a top 4, all of which parts are integrally connected, the top 4 being made by joining together the ends 5 of arms which extend from the ends of the bottom 1 to form the end walls of the box and the top. The side section B is provided with a top flap 6 which laps over the top 4 of the box, and it is also provided with end flaps 7 which fold into the body of the box and engage the end walls 3. The side section C has a top flap 8 which folds over the top flap 6, and end flaps 9 on the side section C fold into the body A of the box and engage the end walls 3 thereof. The flap 6 carries a handle D which forms the locking or closing device of the box. This handle D comprises a strip having arrow-head extremities 10, each of which includes a pair of lugs 11 at opposite sides of the handle to interlock with the ends of a tongue 12 cut out in the flap 6. This tongue is formed by a slit 13 cut in the flap 6 and disposed parallel with the free edge 14, and at the ends of the slit 13 are right-angularly disposed slots 15 through which the extremities 10 of the handle are inserted, and the lugs 11 of the handle engage under the ends of the tongue while the middle or grip portion of the handle is disposed over the tongue. This handle has a limited lateral movement in the slots 15 so as to permit the handle to move to and from locking position. The handle is adapted to interlock with the top flap 8, which is provided with a rectangular opening 16, the ends of which are provided with slots or recesses 17 between which is formed a tongue 18. By moving the handle laterally the ends will engage in the recesses 17, as shown in Fig. 1, and by moving the handle from this position to the position shown in Fig. 2, the top flap is unlocked so that the box can be opened.

If the handle or handle loop is made of cardboard it may be reinforced on the under side by a piece of fabric 19 glued thereto, as shown in Fig. 5.

From the foregoing description taken in connection with the accompanying drawing, the advantages of the construction and method of operation will be readily understood by those skilled in the art to which the invention appertains, and while we have described the principle of operation, together with the device which we now consider to

be the best embodiment thereof, we desire to have it understood that the device shown is merely illustrative and that such changes may be made when desired as are within the scope of the appended claim.

Having thus described our invention, we claim as new and desire to secure by Letters Patent:

A collapsible packing box comprising a body formed of a bottom, top, and end walls integrally connected with the top and bottom; side walls connected with the bottom; end flaps on the side walls folded into the body and engaging the inner faces of the end walls; flaps connected with the top edges of the side walls and overlapping the top of the said body; and a handle in the form of a strip having enlarged ends, one of the last mentioned flaps having recesses out of which

the portion of the handle between the enlarged ends projects, the enlarged ends lying between the top of the body and the said recessed flaps, and the other flap which overlies the top of the body being provided with a longitudinal slot through which the handle projects, and one edge of the slot being recessed for permitting the handle to be laterally moved into and out of the recesses to lock and unlock the flaps.

In testimony whereof we have signed our names to this specification in the presence of two subscribing witnesses.

ABRAHAM MISROCH.
ADOLPH KAHN.
